ARTHUR C. VARNUM, OF AUBURN, AND JAMES E. BIRDSALL, OF SOUTH LAWRENCE, MASSACHUSETTS; SAID BIRDSALL ASSIGNOR TO SAID VARNUM

PICKER-STICK GUIDE AND PICKER CHECK

Application filed October 22, 1928. Serial No. 313,933.

This invention relates to improvements in a combined check and picker stick guide, and guide for the throw of a shuttle.

An object of our improvement is to provide an attachment for looms of any standard type, as the Northrop loom, that is designed to be secured to the under side of the lay with the usual shuttle box located above and on the top of the lay. This attachment is for the purpose of bringing the picker stick to a stop by means of a gradually increased frictional resistance. This attachment provides a device to apply said resistance through the stick controlling the backward movement of the receiving picker, further, this attachment is to prevent the rebound of the stick and attached picker, and elements forcing the shuttle out of the box a distance by the afore-mentioned rebound.

The attachment, in general, comprises a plate that is secured to the under side of the lay, and another plate that is adjustably connected to the first mentioned plate for providing a space between the plates and in which space the picker stick operates. This second plate is formed with an opening, and in this opening is located a spring actuated binder lever having its free end normally resting on the outer face of the second plate, beyond the opening.

An adjustable spring is provided for varying the pressure of the binder lever on the stick. Also, a slot for the adjustment of the lever, (in or out) is provided for the purpose of obtaining a controlling position of greatest resistance to the returning stick, as well as obtaining the necessary amount of grip to prevent rebound.

It is a well known fact that a shuttle will not travel in a straight line through the shed if the force applied to the shuttle, namely by means of the picker, should move in an undesired line, with reference to base plate.

So as to definitely control the line of traverse of the stick and attached picker both with reference to the side play, and parallel, or as nearly as desired parallel motion with the line of the back of base plate and reed. This construction obviates the necessity of depending upon the slot in the lay for guid-

ing the stick in its forward movements in projecting the shuttle.

The device is designed for use on a Northrop single box loom, but is understood as not being limited or confined to any particular make of loom.

In our present construction, the binder lever acts on the stick as the shuttle is entering the box, thus assisting to check the shuttle and preventing the shuttle and stick from rebounding, and forcing out the shuttle somewhat. The present invention is confined solely to the construction of the picker stick check and guide for the throw of the shuttle.

Further objects and nature of the invention will appear in the body of the description, with reference to the drawings and appended claims.

Referring to the drawings:

Fig. 1 is a plan view of the device assembled, showing the picker stick in the space between the plates, and the binder in full lines in its binding operation.

Fig. 2 is a side elevational view showing the spring actuated binder lever in the open- ing in the adjustable plate.

Fig. 3 is a diagrammatic view of the device assembled below the lay and the shuttle box above the lay, and

Fig. 4 is an end view of Fig. 1, looking from the right.

Referring to the drawings in detail:

1 designates the lay part of the loom on which the shuttle travels. 2, is the usual shuttle box secured above and to the lay. 3, is an angular shaped plate that is secured to the underside of the lay by means of bolts located in the elongated openings, 4 in the upper horizontal flange portion 5. The lower integral horizontal flanges 6 and 7 on the plate 3 are formed with elongated openings 8 and 8'. 9 designates the second or outer plate which is formed with the horizontal flange portion 10 and the vertical portion 11. This outer plate is located on and adjustably secured to the flanges 6 and 7 of the plate 3 by means of the bolts 12 and 13 in the elongated openings 8 and 8'. The picker stick receiving

space between the plates 3 and 9 is indicated at 14, and the longitudinal opening at the bottom between the flanges 6 and 7 is indicated at 15 and through which opening the picker stick 16 projects, as shown. The opening 15 extends between the two integral flanges 6 and 7, which determines its length. The outer plate 9 is formed with an opening 17 in the portion 11. 18 designates a pivotally mounted binder lever which is formed with a gradual inclined shaped portion 18', and a straight portion 19 that is formed into an eye 20 for receiving a pin 21, which pin is adjustably secured to the flange 10 of the plate 9 with the nut 22. 23 is a spring having an end 24 which is located in an opening in the head 25, which head is fixedly secured to the upper end of the pin 21. This spring is coiled around the pin 21, as shown, and then extends forward to form the loop 26 and the free end 27. This loop bears against the outer surface of the binder lever 18 for applying pressure thereto. The tension of this spring is adjusted by applying a wrench to the fixed head 25 and turning the same. When the proper tension on the lever 18 is obtained, the nut 22 is tightened. 29 is a piece of leather that is secured to the inside of the free end of the lever 18, for cushioning the blow when this lever returns to the dotted line position in Fig. 1. The face of the binder lever which comes in contact with the picker stick is not here shown as covered with any friction creating material, such as leather fibre, etc., but may be so covered, if desired. The usual lug strap is shown at 30 and the rocker foot construction for the picker stick at 31.

In operation, the shuttle is understood as having been thrown and is entering the shuttle box 2. As it enters the shuttle box, it actuates the picker stick. As the stick is moved rearwardly, it engages the gradually curved surface 18' of the binder lever 18, thus gradually checking the shuttle as well as the stick. This gradual checking of the stick and shuttle prevents any rebound of either the stick or shuttle and minimizes the front pressure of binder lever.

By reason of this adjustment of the front plate on the slotted flanges 6 and 7, the space 15 may easily be set to compel the stick to travel in a straight line between the front and rear plates. Further by reason of adjustment of the rear plate, at each end, the stick and picker may be guided to throw the shuttle in a definite, and desired line. As the shuttle is projected into the box, the gradual inclined surface 18' operates to pinch the stick between this surface and the inner surface 3' of the rear plate 3. By locating the picker check and guide below the lay 1, the accurate operation and guide of the stick does not depend on the dimensions of the usual slot in the lay through which the stick

extends. It will therefore be seen that we have provided a picker stick guide, and adjustment both as to the width of the space and also direction that the shuttle may be guided in its throw and as to varying the tension on the spring which actuates the binder lever inward against the picker stick, and further, by adjustment of lever stud 21, greater resistance to rebound may be obtained.

By varying the position of the pin 21 in the slot 8" and the position of the bolt 13, and the position of the plate 3 by means of the elongated openings 4, the direction of the passageway between the plates 3 and 11 may be changed. That is to say the throw of the shuttle may be varied as to its line of motion through the shed and with relation to the reed. This is an important feature of our picker stick check and guide for the shuttle. By varying the lateral position of the pin 21, in slot 8" the power to drive the stick may be varied, as the angular position of the binder lever is necessarily changed, but the resistance is the same on the stick.

The pin 21 is threaded thru the hub 32 on the flange plate 10. Then nut 22 acts as a lock nut and prevents pin 21 from turning.

What we claim is:

1. In a picker stick check and binding device, said device comprising spaced members to form a stick receiving passageway, one of said members being adjustable and having an opening therethrough, a spring actuated check and binder lever in the opening and extending into the said passageway, one end of said lever being pivotally connected to one of the said members of the device, an adjustable pin on which the said lever is mounted, a spring for varying the tension of the binder lever, for further varying the resistance of the binder and more securely holding the stick against rebound and forcing the shuttle out of the box, said lever being formed with a curved portion which extends into the passageway and with which curved portion the stick engages to gradually bring the picker stick to rest and for retaining the picker stick in a definite position prior to the throw of the shuttle, and for preventing rebounding of the stick.

2. In a picker stick binder device for looms having a stick receiving passageway formed in the lay, one wall of the passageway being adjustable and having an opening, means for adjusting the wall, a pivotally mounted spring actuated stick binder lever formed with a curved part that is located in the said opening and passageway, a part of the lever extending outwardly through the opening and normally resting on the outer side of the adjustable wall, the curved part of the said lever and the spring operating to gradually reduce the rate of motion of the shuttle through the resistance applied to stick and

shuttle receiving picker which is attached to said stick, the binder lever being of such shape as to prevent rebound of stick.

3. A picker stick checking device comprising an adjustable picker stick receiving passageway, a wall of the passageway having an opening, a flange on the wall, a stud bolt adjustably secured to the flange, a binder lever for the picker stick pivotally mounted on the stud bolt and extending into the passageway, a spring on the stud bolt having one end secured to the said bolt and its other end engaging the outer side of the lever; said device being located below and secured to 15 the lay part of the loom.

4. In a loom, a combined check device for the picker stick and shuttle, comprising a pair of spaced members that are secured to and below the lay for controlling the line of 20 movement of the picker stick and for receiving the picker stick, the said stick extending upward through the lay and into the shuttle box on the lay, the construction and arrangement being such that the movements of the 25 stick and shuttle are simultaneously arrested, and means for adjusting one of the spaced members relative to the other for causing the stick to move in a straight line as desired and as described, said adjustable means comprising slotted flanges on one of the spaced 30 members and flanges on the other member and means for securing the flanges together.

5. A picker stick check for looms comprising a pair of parallel members that are secured below the lay of the loom, and spaced from each other to receive the picker stick, and means for adjusting one of said members to vary the space between said members, whereby the movements of the stick will be 40 in a straight line, a stick binder lever in said space, the adjustable member having an opening in which the binder is located, and means for varying the pressure of the binder on the stick.

45 6. A picker stick check device comprising two parallel spaced members, one of the members having upper and lower flanges, the upper flange having bolt receiving openings for attachment to the underside of the lay, the 50 other member comprising a right angle piece which is adjustably secured to the lower flange of the said member and said other member having an opening, a stick binder lever in the opening, and means for adjusting the pressure of the binder on the stick.

7. A picker stick check comprising, in combination, a pair of spaced members, one of the members having an opening, a binder lever in the opening, a spring normally exerting pressure on the binder lever, an adjustable pivot pin for the binder for varying the lateral position of the binder to vary the frictional resistance exerted on the stick, one end of the spring being coiled around the 65 pivot pin and attached to the pin, its other

end engaging the binder lever, means for rotatably mounting the pivot pin on one of the members, means for securing the pivot pin, after the tension of the spring on the binder is determined and means for adjusting the member having an opening relative 70 to the other member.

8. A guide for a picker stick comprising in combination, a pair of spaced plates, a perforated flange, with securing means, means for adjustably securing the plates to the underside of the lay of the loom, a binder lever for the picker stick, a pivot pin for the binder lever, means for laterally varying the position of the pivot pin of said lever to vary 75 the checking effect on the picker stick.

9. A guide for a picker stick comprising a pair of spaced plates, one of the plates having an opening therein, a pivotally mounted and spring actuated binder lever, in the 80 opening and extending into the picker stick space between the plates, the binder lever having a curved surface, means for varying the angular position of the binder lever for 85 varying the frictional resistance on the picker stick and for utilizing less power to drive the stick, as described.
